EDUCATIONAL RESPONDER DEVICE

Steven C. Brandt, Palo Alto, Calif., assignor to Leon Brandt Inc., Palo Alto, Calif., a corporation of California

Filed June 24, 1968, Ser. No. 12,475

Term of patent 14 years

Int. Cl. D19—08

U.S. Cl. D25—1

FIG. 1 is a perspective view, taken from the front and slightly above and to the left of center, of an educational responder device showing my new design;

FIG. 2 is a front view of the responder of FIG. 1;

FIG. 3 is a rear view of the responder of FIG. 1;

FIG. 4 is a side view, taken from the left side, of the responder of FIG. 1; and

FIG. 5 is a bottom view of the responder of FIG. 1.

The essential features of the design reside in the full line portions shown.

I claim:

The ornamental design for an educational responder device, substantially as shown and described.
